United States Patent Office

Des. 181,300
Patented Oct. 29, 1957

181,300

FAMILY ALTAR OR SIMILAR ARTICLE

Boles Liubauskas, Du Bois, Pa.

Application September 18, 1956, Serial No. 42,988

Term of patent 14 years

(Cl. D29—23)

Fig. 1.

Fig. 2.

Fig. 3.

I claim:

The ornamental design for a family altar or similar article, as shown.
